UNITED STATES PATENT OFFICE.

WILHELM HERBST, OF BERLIN-STEGLITZ, AND EMIL DIECKMANN, OF BARMEN-UNTERBARMEN, GERMANY.

FIREPROOF GIRDER.

No. 910,059.

Specification of Letters Patent.

Patented Jan. 19, 1909.

Application filed July 28, 1908. Serial No. 445,752.

To all whom it may concern:

Be it known that we, WILHELM HERBST, and EMIL DIECKMANN, both citizens of Germany, and residents, respectively, of Berlin-Steglitz and Barmen-Unterbarmen, Germany, have invented new and useful improvements in Fireproof Girders, of which the following is a specification.

This invention relates to a fire proof girder which is light, of great strength and may be readily put up.

In the accompanying drawing: Figure 1 is a ground plan of a ceiling provided with our improved girder; Fig. 2 an enlarged section on line A—B—C—D—E—F, Fig. 1, and Fig. 3 a similar section on line G—H, Fig. 1.

In carrying out our invention, we provide a number of preformed reinforced concrete slabs *a*, arranged in pairs, each pair forming the flanks of one of the girders depending from the ceiling. Between each pair of slabs *a*, are interposed one or more preformed reinforced concrete beams *b*, forming the lower face of the girder and provided with a web extending into the interior of the girder, the upper end of such web being roughened. Slabs *a*, as well as beams *b*, are provided with metal cores and are brought to the building in a finished condition. Between slabs *a*, and webs of beams *b*, are formed grooves or channels in which are contained large lumps of spaced beton or chipped bricks *m*, to form air spaces. Upon these bricks or filling pieces are supported beton plates *f*, arranged between the slabs and below the upper ends thereof. Upon plates *f*, is placed a beton layer *c*, which encompasses the upper roughened ends of beams *b*, and will thus, on setting, firmly unite therewith. The main

body of the ceiling is composed of a suitable beton skeleton which does not form part of this invention, the beams *c*, of this skeleton resting directly upon slabs *a*. A beton layer *d*, extends over the entire ceiling and unites with layers *c*, to form an integral body.

In constructing the girder, slabs *a*, and beams *b*, are placed across the walls of the building, a scaffolding *g*, is erected; the ceiling-skeleton is built up on said slabs and scaffolding, the grooves between the tapering bases of slabs *a*, and beams *b*, are filled with cement *n*, the girders are provided with the spaced filling pieces *m* and plates *f*, and finally the beton layers *c*, *d*, are applied. The scaffolding may be removed before the beton layers have completely set.

We claim:

A fire proof girder, comprising a pair of preformed reinforced concrete slabs forming the sides of the girder, a preformed reinforced concrete beam forming the lower face of the girder and provided with a web extending into the interior of the girder, spaced filling pieces between the slabs, plates supported on the spaced filling pieces, and a beton layer supported by the plates, substantially as specified.

Signed by us at Barmen, Germany, this 22nd day of June, 1908.

WILHELM HERBST. [L.S.]
EMIL DIECKMANN. [L.S.]
